UNITED STATES PATENT OFFICE.

PAUL BRESCH, OF PETIT QUÉVILLY, FRANCE, ASSIGNOR TO UNIVERSAL WINDING COMPANY, OF BOSTON, MASSACHUSETTS, A CORPORATION OF MASSACHUSETTS.

TENSION-CONTROLLER.

1,231,560.

Specification of Letters Patent. Patented July 3, 1917.

Application filed January 23, 1914. Serial No. 813,986.

To all whom it may concern:

Be it known that I, PAUL BRESCH, a citizen of the Republic of France, residing at 78 Rue Léon Maletra, Petit Quévilly, Seine Inf., France, have invented certain new and useful Improvements in Tension-Controllers, of which the following is a specification.

My invention relates to tension-controlling devices for regulating the tension applied to a running yarn or thread and is especially adapted for use with winding machines or other textile apparatus. The object of my present improvement is to provide an automatically-operated device for controlling the tension applied to the yarn to compensate for irregularities in the delivery of the yarn at the cop or other source of supply, so as to secure a more constant and uniform ultimate tension on the yarn as it delivers to the machine. For this purpose the essential feature of my improved device consists of a regulating-means adapted to automatically reduce the amount of tension applied to the yarn by the usual tension-device whenever any abnormal resistance to its delivery occurs at the source of supply.

The invention is fully described in the following specification, illustrated by the accompanying drawings, in which like letters of reference designate like parts.

In the drawings:—

Figure 1 is a side elevation of a portion of a winding machine showing a usual form of tension-device employed therewith and illustrating my new controlling-means applied thereto;

Fig. 2 is an enlarged, side view of the tension-device illustrating the arrangement of the tension-controller or regulator in connection therewith;

Fig. 3 is a sectional view of the tension-device taken on the line A—A of Fig. 2, looking in the direction indicated by the arrow a.

Referring first to Fig. 1, I have here illustrated the essential elements of a well-known type of winding machine, but it is to be understood that my new device might also be applied to use in connection with other forms of textile apparatus. In Fig. 1, B designates the winding-spindle on which the bobbin b or other yarn-receiver is supported and rotated and C is the yarn- or thread-guide which acts to traverse the yarn on the bobbin. The thread-guide C is mounted on

a traverse-bar D arranged parallel with the winding-spindle B and is reciprocated from an oscillating rocker-arm E which is connected thereto by the link e. During the operation of the machine the thread-guide C is traversed back and forth with respect to the winding-spindle B to deposit the yarn or thread y in conical courses or layers and the guide C also feeds progressively along the bar to build the cop or bobbin in the form illustrated by the dot-and-dash lines x.

Extending from the main frame F of the winding machine is an arm or bracket G on which is mounted the tension-device H for applying tension to the running yarn y. The bracket G may be of any convenient form appropriate to the style and arrangement of the machine to which the tension-device is applied. The tension-device, proper, for applying resistance to the draft of the yarn may also be of any approved construction such, for instance, as an arrangement of two or more elements having the yarn drawing between them and adapted to press against it to set up a resistance to its movement. I have preferred to here illustrate a form of tension-device comprising two rotatable disks H', H² mounted on a stud or arbor h which is held in a bearing g on the tension-bracket G. The disks H', H² are preferably formed with their peripheries flared outwardly at h², as illustrated more particularly in Fig. 3, to provide a trough-like guideway which facilitates the threading of the yarn y in between their opposed faces. A double-loop, auxiliary wire-guide T is secured to the bracket G and partly surrounds the rims of the disks H', H² to also assist in leading the yarn into place between them. Loosely mounted on the outer end of the stud h is a cup-shaped cap or thimble h³ arranged with its inner end bearing against the outer face of the disk H². The inner disk H' bears against a washer j which abuts the end of a hub k, formed as a part of a wheel K, the latter being fixed on the shaft h. The wheel K may be made in the form of a pulley, gear or ratchet-disk and is employed as a turning element for the shaft h and disks H', H², the mechanism for rotating the disk not being here shown as it forms no part of the present invention.

The thimble h³ is employed for forcing the disk H² toward the disk H' and any suit-

able means may be used for applying pressure to the thimble, such as springs or levers arranged to bear upon it. As here illustrated, I make use of a lever L having an arm l adapted to bear against the end of the thimble h³ and a second arm l' on which are suspended weights m. The lever L is preferably formed of wire coiled helically at l², l³ to form bearings for receiving the pivot-pin N which projects through lugs g², g³ on the bracket G. The arm l of the lever L extends vertically and is formed with a horizontal cross-piece l³ positioned to reach across the outer end of the thimble h³. The other arm l' extends horizontally and is formed with a loop l⁴ adapted to receive the disk-like weights m which may be added or subtracted in accordance with the amount of pressure it is desired to apply to the disks H', H². It will be obvious that in place of the above described tension-disks the well-known hinged plates or grid-members might be employed for the same purpose.

25 Referring again to Fig. 1, I have here illustrated a tension drop-wire O mounted on the tension-bracket G and arranged with the yarn y drawing under its end o. The drop-wire O serves as a stopping-lever to arrest the operation of the machine when the yarn y breaks or becomes exhausted. I have also shown a compensating-lever P pivoted on the bracket G and arranged with its end p adapted to engage the yarn y as it leads under the drop-wire O. The lever P acts to alternately take up and release a length of yarn y' to compensate for the difference in draft on the yarn as it winds from the large diameter of the bobbin down to the small diameter and vice versa. These two members O and P are not necessary to the proper working of my present invention, however, and are therefore not described in detail. They are shown in the drawings merely to illustrate the course of the yarn as it leads from its source of supply to the winding-spindle B on which it is wound into the cop or bobbin. In fact, the parts of the machine already described are all well-known and have been long in general use. The novel feature of the invention which operates in connection with these known elements will now be described:

55 Referring particularly to Figs. 2 and 3, my improved tension-regulating means consists essentially of a lever R adapted to be controlled by the yarn y before the latter enters the tension-device H and arranged to relieve the pressure of the lever L on the disks or other tension-elements whenever any undue resistance to the delivery of the yarn occurs at the supply-cop Y. The lever R as here shown is pivoted on the bracket G by means of a stud or pin r, but it might 60 be mounted in any other suitable manner.

In order to make the lever R relatively light in weight and less susceptible to the effects of inertia and momentum I preferably construct it of wire. To form a bearing for the pivot of the lever R, I coil the wire on itself at r' and the two ends of the coil extend at substantially right-angles to each other in the arms r², r³. The arm r² reaches down below the tension-device H and is formed at its end with a "pigtail" or guide-eye r⁴. The other arm r³ is arranged to pass under the outwardly bent end l³ of the tension-lever L, reaching downwardly therefrom and terminating in the hook or loop r⁵. The loop r⁵ is adapted to receive perforated weights w, and the proper number of these are applied to balance the lever R to maintain its arm r³ just in contact with the end of the tension-lever L. The supply-cop Y for the yarn y is usually held on a spindle S arranged below the tension-device, and above its end I prefer to employ a "pigtail" or guide-eye s through which the yarn passes as it leads from the cop. It will be noted that the "pigtail" or guide-eye r⁴ is normally positioned outwardly beyond a direct line drawn from the guide-eye s to the tension-guide T, and therefore the yarn will make a bend as it passes through the guide-eye r⁴. This is necessary for the proper 85 operation of the device as later described. The method of operation of the whole arrangement is as follows:

The yarn y is drawn up from the supply-cop Y through the pigtail s, thence through the guide-eye r⁴ at the end of the lever R, and then across the wire-guide T and between the tension-disks H', H². From the tension-device H the yarn leads under the end of the drop-wire O, making a loop y' over the end of the compensator P, and then draws up through the thread-guide C, having its end secured to the bobbin b. When the operation of the machine is started the yarn is wound on the bobbin b, while being 110 traversed by the guide C as before described, and as it passes through the tension-device H a slight resistance to its draft is imparted thereby to provide the proper tension for securing the coils of winding in place. The 115 amount of tension applied to the yarn may be varied as desired by placing a greater or less number of weights on the lever L to regulate the pressure of the arm l on the thimble h³ and the pressure of the latter on the disk H². Normally, with the yarn y delivering freely from the supply-cop Y, the tension applied thereto will remain substantially constant and uniform and hence the yarn will deliver from the thread-guide C 125 to the bobbin with the required evenness. It has been determined in practice, however, that very often the supply-cops are not wound properly and therefore they will not always deliver their yarn freely without 130

hitch or hindrance. When a hitch or unevenness in delivery occurs at the supply-cop this naturally sets up an increased resistance to the draft of the yarn and hence 5 the original tension on the yarn is considerably augmented unless some means is provided to relieve or decrease the normal or applied tension. It is for this purpose that the controlling-lever R is arranged to act 10 automatically in the following manner: Whenever the free delivery of the yarn from the cop Y is hindered or restricted the abnormal pull of the yarn will act on the lever R to depress its arm r^2 , as illustrated 15 by the dash-lines in Fig. 2, and this action causes the arm r^3 to be raised against the arm l' of the lever L. As the arm r^3 is carried upwardly it tilts the lever L against the action of its weights m and releases the 20 pressure of its arm l on the thimble h^3 . In this way the pressure of the disks H' , H^2 on the yarn, as it passes between them, is either partially or entirely relieved in accordance with the amount of resistance to 25 delivery encountered at the supply-cop, and a more uniform, ultimate tension is thereby maintained on the yarn as it delivers to the winding-spindle. By varying the number of weights w on the lever R the operation 30 of the latter can be regulated to give the proper response to variations in the delivery of the yarn at the supply-cop; and in this way a very sensitive control is maintained. My improved controller is designed to act, 35 not only when the yarn catches on the supply-cop and is thereby hindered in its unwinding therefrom, but also in response to other variations in delivery. For instance, the yarn will unwind much more freely from 40 a full cop than from one nearly exhausted, and the present device is adapted to sense any such gradual variation in the delivery of the yarn and to automatically operate the tension-device to regulate the applied tension 45 in conformity therewith. It has been demonstrated that with the present improvement applied to a usual form of tension-device the yarn can be unwound at a greatly increased speed, with less breakages, and 50 without imposing as much strain on the material.

Various modifications might be made in the form and structure of the parts of my new device without departing from the 55 spirit or scope of the invention; therefore, without limiting myself to the exact construction shown and described, what I claim is:—

1. The combination with a tension-device 60 comprising two disks between which the yarn draws and means to apply pressure on the disks to cause them to press upon the yarn, of a controlling-means arranged intermediate the disks and the source of supply 65 of the yarn, said controller adapted to

be operated automatically by the action of the yarn before it enters the tension-device to relieve the pressure on the disks whenever the resistance to delivery of the yarn at the supply becomes abnormal. 70

2. The combination with a tension-device comprising members adapted to bear upon the yarn to apply tension thereto, and a lever to operate said tension-members, of a separate controller-lever arranged to move 75 independently of the tension-lever and adapted to actuate said tension-lever to relieve the tension on the yarn, said controller-lever arranged in the path of the yarn to be acted upon by the yarn before the latter 80 enters the tension-device as it draws between its source of supply and the tension-device and adapted to be moved thereby whenever the delivery of the yarn is restricted or impeded. 85

3. The combination with a tension-device comprising tension-members adapted to bear upon the yarn to apply tension thereto, and a lever for applying pressure to said tension-members, of a separate controller-lever 90 arranged intermediate the tension-device and the source of supply of the yarn, said controller-lever free to move independently of the pressure-lever having one end engaged by the yarn before the latter enters 95 the tension device and its opposite end engaging the pressure-lever to operate the latter to relieve the pressure on the tension-members whenever abnormal resistance to the delivery of the yarn occurs at the supply. 100

4. In a tension-device, the combination with tension-members adapted to bear upon the yarn to apply tension thereto, and a lever to operate said tension-members, of a pivoted controller-lever arranged in the 105 path of the yarn as it draws from its source of supply to the tension-members with one end to be acted upon by the yarn before the latter enters the tension-device and the opposite end engaging the tension-lever, and 110 weights on said controller-lever adapted to balance it against the normal pull of the yarn but to allow it to be moved to operate the tension-lever whenever the draft on the yarn is abnormally restricted at the supply. 115

5. In a tension-device, the combination with members adapted to bear on the yarn to apply tension thereto, and a lever to operate said tension-members, of a controller-lever adapted to actuate the tension-lever to relieve its operative effect, said controller-lever having a guide engaged by the yarn before it enters the tension-device, and means on said controller-lever to balance it against the normal tension of the yarn to 120 maintain its guide out of alignment with the supply-cop and the tension-members whereby any abnormal resistance to the delivery of the yarn will act to move said lever to actuate the tension-lever. 125

6. In a tension-device, the combination with tension-members adapted to bear on the yarn to apply tension thereto, and a lever to apply pressure to said tension-members, of a controller-lever formed with two arms, one of which is adapted to engage the end of the pressure-lever to raise the latter and relieve its pressure on the tension-members, and the other arm having a guide through which the yarn leads before

it enters the tension-device, and weights on the controller-lever to normally restrain it from acting on the pressure-lever.

In testimony whereof I affix my signature in presence of two witnesses.

PAUL BRESCH.
